John L. Hadden, of Philadelphia, Pa.
Letters Patent No. 1750. Dated, Apr. 28, 1863.

The Schedule referred to in these Letters Patent, & making part of the same.

To all whom it may concern.

Be it known that I, John L. Hadden, of the city of Philadelphia in the State of Pennsylvania, have invented or produced, a new and original Design for a cover for the wash-kettles or large boilers of stoves, and I do hereby declare that the following is a full and exact description of the same, reference being had to the accompanying drawings, making a part of this specification, in which figure 1. is a plan view of the upper side of the said cover, and figures 2 and 3 central longitudinal and transverse sections, respectively, of figure 1. like letters indicating the same parts, when in the different figures.

The wash-kettles or boilers of stoves are large oblong vessels, generally, requiring raised covers of much greater areas than can be produced from the tin plate, out of which the same are always made, without seaming or splicing: and

Mar. 1750

consequently, their top portions are without the uniformity and smoothness of surface which is desirable both for cleanliness and durability in use.

The object of the present design is to afford a shape or form for the top portion of the raised cover of such vessels, which will admit of the use of sheet iron in a single piece, to form the top portion of the same. And my invention or production consists in making the top of the cover in the shape or form shown in the drawings. It may be described negatively by stating that the top portion of the cover is without any joint or seam; but in more exact and positive terms, that it consists of a single piece of sheet iron cut into an oblong form, and having parallel sides e. e. and ends f. f. connected by curved corners g. g. g. g. and formed up within these boundaries so as to produce a smooth surface with both flat and raised portions, as shown in the drawings - in which a. a. are the flat portions. b. b. the raised portions starting from the said flat portions (a. a.) and c. c. the raised portion starting from the highest part of the raised portion b. b. These three distinct portions are connected together immediately by short counter-curves d. d. instead of sharp angles - which are sometimes seen in the raised work of thin tin plate; and the successful formation of this my design, in sheet iron, depends much upon the counter-curves (d) being free from anything like an angle, or upon being made of the curved shape seen in figures 2 & 3.

What I claim as my invention or production, and desire to secure by letters patent, the described shape or form, in sheet-iron, as a design for the covers of large wash-kettles or boilers of stoves.
